(57) **CLAIM**

We claim the ornamental design for a light fixture, as shown and described.

DESCRIPTION

FIG. 1 is a perspective view of a light fixture showing our new design.

FIG. 2 is another perspective view of the light fixture shown in FIG. 1.

FIG. 3 is a side view of the light fixture shown in FIG. 1.

FIG. 4 is a side view of the light fixture shown in FIG. 1,

coupled to a support member; and,

FIG. 5 is a bottom plan view of the light fixture shown in FIG. 1.

The broken lines shown in the drawings illustrate portions that form no part of the claimed design. The support member, which is shown in broken lines in FIG. 4, forms no part of the claimed design.
